[57] **CLAIM**

The ornamental design for a portable power brush housing, as shown and described.

DESCRIPTION

FIG. 1 is an environmental top perspective view of a portable power brush housing, shown with attachments, showing my new design;

FIG. 2 is a bottom perspective view of the portable power brush housing of FIG. 1;

FIG. 3 is a left side elevational view with the right side being a mirror image thereof;

FIG. 4 is a front view with the rear being a mirror image thereof;

FIG. 5 is a top view thereof; and,

FIG. 6 is a bottom view thereof.

The broken lines showing the rechargeable adapter holes and the power switch in FIGS. 1-5, the attachments in FIG. 1, and the hand and brush in FIG. 3 are for illustrative purposes only and form no part of the invention.

The stem extension in FIG. 1 is broken to indicate indefinite length.
